LAMP RELEASER

Harold D. Grinnell, Pittsfield, Mass., assignor to
The G. C. A. Manufacturing Co., Pittsfield,
Mass., a corporation of Massachusetts

Application November 7, 1938, Serial No. 239,207

6 Claims. (Cl. 294—20)

This invention relates to apparatus for removing electric light bulbs, particularly those of large size, from sockets of the pull type. It is particularly directed to improvements in devices of the general type shown in my prior Patent No. 1,520,946, December 30, 1924, to provide an apparatus which will be capable of handling bulbs of larger size and with less clearance between the bulb and the surrounding reflector or shade. A further object is to prevent injury to the workman in case the bulb should be broken in removal or should come loose before being properly grasped by the device. A further object is to provide a mechanism of this type which will be of exceptionally light weight, so that it may be of a size to handle bulbs of large size but will still not be unwieldy when mounted on the end of a long pole. A further object is to provide a lamp remover in which the opposed grasping fingers will be electrically insulated from each other to avoid accidental short circuiting if the fingers contact any part of the electrical wiring. Additional objects will appear from the following description and claims.

25 Referring to the drawings:

Fig. 1 is a front elevation of a device constructed in accordance with my invention;

Fig. 2 is a side elevation thereof;

Fig. 3 is a detail similar to Fig. 1 but showing 30 the tongs in open position;

Fig. 4 is a detail corresponding to Fig. 3 showing the tongs being introduced between the bulb and the surrounding reflector;

Fig. 5 is a similar detail showing the tongs 35 grasping the flange of the socket;

Fig. 6 is a section on line 6—6 of Fig. 1;

Fig. 7 is a section on line 7—7 of Fig. 1;

Fig. 8 is a section on line 8—8 of Fig. 1;

Fig. 9 is a section on line 9—9 of Fig. 1; and

Fig. 10 is a section on line 10—10 of Fig. 1.

The device is supported on a square tube 11, preferably of sheet aluminum alloy, embracing and secured to a wooden plug 12 (Fig. 9) cylindrical at its lower end and provided with an aluminum sheath 13. This sheath is provided with a spring pressed ball catch 14 by which the device may be secured releasably to a ferrule 15 on the upper end of a long pole 16.

On this tube are supported the lower ends of 50 relatively long grasping fingers by some mechanism maintaining said lower ends at a substantially constant distance apart. Preferably this mechanism consists of a sliding frame which will now be described. Freely slidable on the square 55 tube 11 is a lower frame member 17 especially

fabricated to secure lightness and strength and to insulate it from the tube. The frame is composed of two side plates 18 of sheet insulation, preferably of a fabric base impregnated and coated with an artificial resin which may be one of the phenolic condensation products. These side plates are reenforced throughout their length by strips 19 held thereto by tubular rivets 20. If the electrical insulation of the fingers is not important the strips may be of metal; if insulation 5 is desired they are preferably made of the same material as the plates. Use is repeatedly made of this type of construction, so that its advantages may be pointed out now to avoid later repetition. The insulating sheet itself has strength in its 15 plane, but is flexible as to forces applied transversely. By laminating the sheet with the strip a much stronger plate results. At the same time the insulating properties of the sheet can be preserved by making the reinforcements of the same 20 material; or, if the reinforcements are to be of metal, by terminating them short of any point to which the transmission of current is to be prevented. The plates are notched at 21 to receive ears 22 extending from cross plates 23 (Fig. 6) 25 perforated for lightness and forming together with the side plates a box structure slidably up and down on the tube 11. On each side the plates 18 are also reenforced by aluminum cast frames 24 having lugs 25 engaging the ears 22 on the 30 cross plates. The castings are secured together by hollow pins 26 secured as in the case of the upper frame to be described. The pins pass freely through a slot 27 in the tube, the slot being sufficiently larger than the pins so that the latter 35 never make contact with the metal tube.

Pivoted to the ends of the lower frame 17 as by hollow pins 30 are the main socket grasping fingers 31 having notches 32 adjacent their upper ends to receive the flange 33 of a socket 34 40 of the pull type. These fingers are preferably formed of cast aluminum suitably apertured for lightness, and transversely curved to conform to the socket 34 and to the electric light bulb 35 carried by it. The pins 30 may be anchored in any desired way, but preferably by clips 36 having their ends 37 (Fig. 1) turned over the edges of the strips 19 and the plates 18, and having perforated lugs 38 through which, and the pins 30, cotter pins 39 may be passed. The clips serve not only 45 to assist in transmitting stress between the fingers and the frames but to give a permanent anchorage for the cotter pins.

At an intermediate point of their length the 50 fingers 31 are coupled as by links 40 to the up- 55

per end of the tube 11. For this purpose the tube 11 is provided with opposed cap pieces 41 secured together by a hollow pin 42 (Figs. 1, 3, and 6) headed over at one end and secured by a cotter pin 43 at the other. The cap pieces are provided with recesses 44 (Fig. 7) at their ends into which fit pins 45 of insulating material. The pins pass through holes in the lower ends of the links 40, and between the links and the cap pieces pass 10 through strips 46 of insulation and through side extensions 47 of the material of the tube 11. The insulation serves not only to insulate the links from the tube, but as upper anchorages for certain operating springs as will be pointed out below. The outer ends of the links are pivoted to the fingers by hollow pins 48 received in holes in the fingers and secured to the links by cotter pins (not shown).

The lower frame 17 slides freely upon the tube 11 in order to permit rocking movement of the links 40, and thus the linkage described determines the path of movement of the fingers 31 but does not actually cause their movement. To operate the fingers under the control of the user 25 there is provided an upper slide 50 positively controlled in a direction causing opening of the fingers and spring controlled in the direction which causes closing of the fingers. This upper frame is generally similar to the lower frame in construction, having side plates 51, external reenforcing strips 52 and 53, and internal reenforcing strips 54 secured as in the former case by hollow rivets (Fig. 8). The frame is provided with cross plates 55 and castings 56 constructed and functioning as in the previous case. The pin 57 by which the two castings are secured together is longer than pin 26 so that it passes through two links 58 pinned at 59 (Fig. 3) to a lever 60 pinned to the tube 11 at 61. The pin 61 is preferably insulated from the tube 11 and ferrule 13 by insulating bushings 61'. Pin 57 is headed over at one end, and is secured at the other end to one of the links by a cotter pin 62 (Fig. 6). The lever 60 may be provided with a rope 63 (Fig. 3) by which 45 the lever may be rocked downwardly to lower the upper slide by an operator holding the lower end of the pole. The plates 51 preferably overlap the strips 46 in all positions to prevent possible misalignment.

50 To raise the upper slide it is connected by tension springs 65 with the upper end of the tube 11. For this purpose the pair of insulating strips 46 previously referred to are slotted at their ends on their upper edges to receive metal cross pieces 55. 66 (Fig. 8) which are themselves slotted to interfit with and thus to retain firm position on the strips. Each cross piece 66 is also notched centrally to receive an end loop of one of the springs 63. A loop on the lower end of the spring is attached to a similar cross piece 67 held in place between ears 68 (Figs. 3 and 8) formed from the internal reenforcing strips 54. By the force of the spring the upper slide is urged upwardly, in the opposite direction from that given by pulling 60 on the rope 63, operating through the mechanism now to be described to cause closure of the fingers.

On the upper portion of the upper slide 50 opposing side plates are joined by hollow rivets 70 70 (Fig. 10) surrounded freely by rollers 71, preferably of insulating material, the rivets preferably being held by clips 72 similar to the clips 36 previously described. As the frame reciprocates the rollers ride upon a cam 73 formed on the outer surface of the fingers and embodying

a curved portion 74 and a straight locking portion 75 having an angularity sufficiently small to prevent any outward movement of the fingers. The coaction of the rollers and the cams forces the fingers inwardly when the springs 65 draw the upper frame upwardly, the links 40 rocking and the lower slide 17 rising to permit this motion. When the lever 60 is rocked to lower the upper frame, the fingers tend to sink by their own weight and to carry the lower frame down with them. In this downward movement the resulting swinging of the links 40 carries the fingers outwardly. If for any reason the lower slide should stick, it will be moved downwardly by the positive contact of the box-like structure of the two frames where they surround the tube 11.

In order to prevent a bulb, or the fragments of a shattered bulb, from dropping, a fabric bag 80 is secured to a frame 81 shown as consisting of a metal base 82 with upstanding sides and 20 light, flexible sides 83 preferably of the same insulating material as was used in the construction of the sliding frames. The bag receives the sides of the bulb practically completely, and prevents its dropping by its premature loosening from the 25 socket; and also prevents fragments of a bulb from dropping if it is accidentally shattered.

Referring particularly to Figs. 4 and 5, it will be seen that while the device is useful in extracting bulbs and sockets of any pull type, it is particularly useful in cases where the external reflector or shade 85 is spaced very closely to the bulb, so that the fingers have only a slight clearance in which to enter and then to shift their position in order to grasp the socket flange. In the case for which the device of the present invention was originally designed this clearance was only $\frac{3}{8}$ ". At the same time the larger sized bulbs have a ratio between maximum bulb diameter and socket diameter much higher than is true with smaller sizes. This means that the fingers not only have to pass through a small aperture, but have to tilt sufficiently to grasp the socket while leading their intermediate portions around the bulb in close proximity thereto. A parallel motion such as shown in my Patent No. 1,520,946 will not produce this double effect with as little clearance as is necessary in the conditions for which the present invention was designed.

In the present instance the lower ends of the clamping fingers are carried on vertically reciprocating pivots, although it is apparent that a pair of links pivoted to the tube 11 would furnish support in somewhat the same manner. The motion given to the fingers is thus almost entirely one of tilting as may be controlled by the links 40. Suitable variations in this motion for special conditions may be controlled by changing the lengths and pivotal points of the links; as suggested above by substituting a supporting linkage for the lower sliding frame; and by changing the lengths of the fingers themselves.

I claim:

1. In a device for removing lamps from sockets, a pair of grasping fingers having free grasping ends, a pole-carried support, links connected to said support and to intermediate points on the fingers and diverging in a direction towards the free ends of the fingers, a slide mounted on 70 said support, pivots connecting said slide with the other ends of the fingers, a second slide on the support engageable with the fingers intermediate their lengths, the contacting surfaces of said second slide and said fingers being shaped 75

for cam action, spring means for shifting the second slide on the support in a direction to cause said cam action to close the fingers, and manually operable mechanism for causing movement of the second slide in the opposite direction, said contacting surfaces being formed at such an angle as to be irreversible when the fingers are in grasping position.

5. 2. A pole-supported lamp removal device for lamps of the pull-socket type, having socket-engaging fingers and actuating means therefor, in combination with a flexible bag and means for positioning the bag in open condition between the fingers.

10. 3. A pole-supported lamp removal device for lamps of the pull-socket type, having socket-engaging fingers and actuating means therefor, in combination with a flexible bag and a flexible bag support carried by the pole in position to hold the bag in open condition between the fingers.

15. 4. A lamp removal device comprising a support, opposed fingers having free ends shaped to conform to and grasp a portion of the lamp to be removed, a slide movable lengthwise on the support and having pivotal connection with the fingers at the opposite ends thereof, an intermediate slide movable lengthwise on the support and having cam connection with intermediate portions of the fingers, links connecting an intermediate portion of each finger with the support, and means for moving the intermediate support in one direction to cause operation of said cam connections or in the other direction to make contact with the first support to cause the fingers to be separated by outward swinging of said links.

20. 5. A lamp removal device comprising a support, opposed fingers having free ends shaped to conform to and grasp a portion of the lamp to be removed, a slide movable lengthwise on the support and having pivotal connection with the fingers at the opposite ends thereof, an intermediate slide movable lengthwise on the support and having cam connection with intermediate portions of the fingers, links connecting an intermediate portion of each finger with the support, and means for moving the intermediate support in one direction to cause operation of said cam connections or in the other direction to make contact with the first support to cause the fingers to be separated by outward swinging of said links.

25. 6. A lamp removal device comprising a support, opposed fingers having free ends shaped to conform to and grasp a portion of the lamp to be removed, a slide movable lengthwise on the support and having pivotal connection with the fingers at the opposite ends thereof, an intermediate slide movable lengthwise on the support and having cam connection with intermediate portions of the fingers, links connecting an intermediate portion of each finger with the support, and means for moving the intermediate support in one direction to cause operation of the cam connections or in the other direction to make contact with the first support to cause the fingers to be separated by outward swinging of said links.

30. 7. A lamp removal device comprising opposed fingers having free ends shaped to conform to and grasp a portion of the lamp to be removed, three mutually movable members, pivotal connections between the opposite ends of the fingers and one of the members, links connecting an intermediate portion of each finger with a second member, locking cam connections between the fingers and the third member, and means for causing relative movement between the members.

HAROLD D. GRINNELL. 35
